GOVERNING APPARATUS

Ozro N. Bryant, Prospect Park, Pa., assignor to
Westinghouse Electric & Manufacturing Com-
pany, East Pittsburgh, Pa., a corporation of
Pennsylvania

Application May 31, 1934, Serial No. 728,257

5 Claims. (Cl. 264—14)

My invention relates to pressure developing means of the type particularly suitable for use in fluid-pressure governing apparatus and it has for an object to provide pressure developing means which shall be economical in the consumption of power.

In fluid-pressure governing apparatus having impellers for developing pressure for governing, it has been found that excessive power consumption may be involved, particularly in connection with the governor impeller. In accordance with the present invention, instead of the pressure range for governing or control purposes being afforded by an impeller device of special design to give a governing pressure range, the pressure range is afforded by a centrifugal escape device. In other words, I provide a source of fluid under pressure, which may be provided by an ordinary centrifugal pump, the magnitude of the pressure or changes in which are immaterial so long as the pressure is sufficiently high, and pressure from such source is supplied through an orifice to a passage, the passage furnishing fluid under pressure to suitable pressure-responsive means and the other end of the passage having a centrifugal escape device in communication therewith, the escape device functioning to modify the pressure in the passage so that such pressure varies substantially as the square of the speed of the turbine. Accordingly, a further object of my invention is to provide apparatus of this character having these advantageous features of construction and of operation.

A further object of my invention is to provide pressure developing means wherein fluid is supplied from a suitable source through an orifice to a passage, the passage communicating with suitable pressure responsive means and having the pressure therein controlled by a suitable centrifugal resistance arrangement.

These and other objects are effected by my invention as will be apparent from the following description and claims taken in connection with the accompanying drawing, forming a part of this application, in which:

Fig. 1 shows a side elevational view of a turbine with my improved pressure-developing means for the governing apparatus thereof applied thereto; and

Fig. 2 is a detail view of a modified form of pressure developing means.

Referring now to the drawing more in detail, in Fig. 1, I show a turbine including a stator structure 10 and a rotor 11. The admission of elastic fluid to the turbine is controlled by a suitable

admission valve 12, operated by servo-motor apparatus, at 13, controlled by a pressure-responsive device 14. The apparatus so far described is conventional and needs no further description, it being merely necessary to bear in mind that the pressure-responsive device 14 acts in response to pressure change in one direction to move the admission valve in one direction and vice versa.

The pressure-responsive device 14 is supplied with fluid under pressure by a passage 15, such passage having fluid supplied thereto from a suitable source through an orifice and variation of pressure therein being secured by an escape device which functions to set up resistance to escape varying as a function of the turbine speed.

More particularly, I show the passage 15 extending into the stator structure and communicating with an annular chamber 16 formed between the interior of the axial bore 17 of the stator structure and the rotor 11. The stator structure also has formed therein an impeller chamber 18. An impeller 19 is arranged in the impeller chamber and is carried by the rotor 11, the impeller having an eye 20, supplied from the fluid pressure supply 21.

Fluid under pressure from the impeller chamber 18 is supplied through the orifice 23 to the passage 15. Means, for example, spaced packing rings 24, are carried internally of the bore 17 and cooperate with the rotor 11 to define the aforesaid annular chamber 16, the latter preferably including an annular channel 25 formed in the stator structure 10. The rotor of Fig. 1 is formed with a transversely extending and inclined passage 27, one end of the latter communicating with the annular chamber 16 and the other end communicating with the drain space 28.

Assuming that the rotor is rotating, it will be apparent that the column of liquid from the axis to the end of the inclined passage 27 which communicates with the annular chamber 16 sets up resistance to escape, that is, a head of liquid is developed, due to centrifugal force, which resists escape from the annular chamber. In other words, the inclined passage provides for a pressure in the supply passage 15 which varies as the square of the diameter of the portion of the rotor having such inclined passage, as the density or specific gravity of the liquid, and as the square of the speed of the rotor.

As already pointed out, the pressure developed in the impeller chamber is immaterial so long as it is above the operating pressure in the passage 15. Any excess flow above that required for gov-

25

erning escapes through the inclined passage 27.

The flow through the orifice 23 varies as the square root of the pressure difference thereacross. Perhaps certain figures, given by way of example, may make the flow operation somewhat clearer. Assuming that the impeller pressure is 90 pounds and that the pressure in the line 15, which depends upon the rotor diameter, liquid density, and the square of the rotor speed, is 40 pounds 10 the flow through the orifice would vary as the square root of 50, that is 7; and, if the impeller pressure is reduced to 70 pounds, the supply pressure still remaining at 40 pounds, then the flow would be the square root of 30 or 5½, the escapes 15 under the two conditions being in the ratio of seven to five and one-half.

From the apparatus so far described, it will be apparent that the diameter of the rotor in the vicinity of the centrifugal escape device is important where centrifugal head of fluid is depended upon to afford the resistance to escape, it being borne in mind that the pressure in the governor passage 15 varies directly as the square 20 of the diameter of the rotor and directly as the square of the speed thereof. Accordingly, I show the spindle modified to provide for variation in the diameter of the portion thereof cooperating with the pressure developing means. To this end, knowing the speed of the turbine and the 25 desired pressure, a bore 17 of suitable diameter is provided and the spindle 11 has an annular member 29 fixed thereto, the member 29 being of the desired diameter and the passage 21 being formed both in the member 29 and in the rotor 30 structure proper. Assuming that a pressure of 40 pounds of a given governing oil is desired in the governing passage 15, then, for a speed of 3600 R. P. M., if a shaft diameter of 5 inches is required, for a speed of 1800 R. P. M., a shaft 35 diameter of 10 inches would be required, and, for a speed of 900 R. P. M., a shaft diameter of 20 inches would be required.

From the figures last referred to, it will be apparent that if the turbine is of small size and the 40 speed is low, the diameter of the centrifugal escape device may be excessive. Accordingly, in Fig. 2, I show means which is essentially the same in principle as that shown in Fig. 1 except that means is provided for increasing the mass factor 45 of the centrifugal resistance. In Fig. 1, as already pointed out, this resistance is afforded by the head of liquid between the rotor axis and the end of the inclined passage communicating with the annular chamber 25. In Fig. 2, instead 50 of relying upon the centrifugal head of liquid, I provide the spindle 11 with one or more radial passages 31 communicating with the annular chamber 16 and each passage having a valve seat 32 at its end. A ball valve 33 cooperates with 55 each seat 32, and it will be apparent that the centrifugal resistance to escape of fluid from the annular chamber 25 and through the passage or 60 passages 31, is dependent upon size and the density or specific gravity of the ball or balls 33. By 65 using balls made of heavier or lighter materials, or varying the size thereof, it will be apparent that the diameter of the portion of the rotor provided with the centrifugal escape device may be made independent of the turbine speed and rotor 70 or spindle size.

While I have shown my invention in several forms, it will be obvious to those skilled in the art that it is not so limited, but is susceptible of various other changes and modifications, without departing from the spirit thereof, and I 75

desire, therefore, that only such limitations shall be placed thereupon as are imposed by the prior art or as are specifically set forth in the appended claims.

What I claim is:

1. In control mechanism, a pressure responsive device, a stator structure having an axial bore, a rotary member extending into the bore, means carried by the stator structure and cooperating with the rotary member to provide an annular chamber, a source of fluid under pressure, a passage for supplying fluid under pressure to the pressure responsive device and communicating with said annular chamber, an orifice for supplying fluid from said source to the passage, and a diagonal passage extending transversely of the rotary member, one end of said diagonal passage communicating with the annular chamber and the other end communicating with exhaust space. 5

2. The combination with a prime mover having a rotor, motive fluid admission means, of a governor controlling the admission means, said governor including a passage for liquid under pressure, means responsive to pressure in said passage for controlling the admission means, escape means for the passage and operating in response to speed of the rotor to provide pressure in said passage varying as a function of the rotor speed, means operated by the rotor for developing liquid 10 under pressure which is greater than the passage pressure, and an orifice for supplying liquid from the last-named means to the passage, whereby said passage is maintained filled with liquid from the orifice at a pressure determined by the escape 15 device and excess liquid supplied to the passage from the orifice flows through the escape device 20 without affecting the pressure in the passage. 25

3. The combination with a prime mover having motive fluid admission means, of a governor controlling the admission means, said governor including a passage for liquid under pressure, means responsive to pressure in said passage for controlling the admission means, a rotor construction 30 operated by the prime mover, means including the 35 rotor construction providing an annular chamber forming a part of the passage, escape means carried by the rotor construction and communicating with said chamber and utilizing centrifugal force due to rotation of the rotor construction for 40 providing resistance to escape of liquid from the passage varying as a function of the speed of the rotor construction, means operated by the prime 45 mover for developing liquid under pressure which is greater than the passage pressure, and an orifice for supplying liquid from the last-named means to the passage, whereby said passage is maintained filled with liquid from the orifice and 50 at a pressure determined by the escape means and excess liquid entering the passage from the orifice flowing through the escape means without 55 affecting the pressure in the passage. 60

4. The combination with a prime mover having motive fluid admission means, of a governor controlling the admission means, said governor including a pressure responsive device operatively connected to the admission means, a passage for supplying liquid under pressure to the pressure responsive device, stationary structure having a cylindrical bore, a rotor construction operated 65 by the prime mover and having a portion extending through the bore, spaced sealing means carried by the stationary structure internally of the bore and cooperating with said portion of the rotor construction to define an annular chamber. 70

ber forming a part of said passage, escape means carried by the rotor construction and communicating with the annular chamber and utilizing centrifugal force due to rotation of the rotor construction to afford resistance to escape of liquid from the passage varying as a function of the speed of the rotor construction, means operated by the rotor construction for developing liquid under pressure which is greater than the passage pressure, and an orifice for supplying liquid from the last-named means to the passage, whereby said passage is maintained filled from the orifice and at a pressure determined by the escape means and excess liquid entering the passage from the orifice flowing through the escape means without affecting the pressure in the passage.

5. The combination with a prime mover having motive fluid admission means, of a governor controlling the admission means, said governor including a passage for liquid under pressure, means responsive to pressure in the passage for controlling the admission means, means providing an

annular chamber forming a part of said passage, a rotor construction operated by a prime mover, escape means carried by the rotor construction and communicating with the annular chamber and utilizing centrifugal force due to rotation of the rotor construction for affording resistance to escape of liquid from the annular chamber varying as a function of the speed of the rotor construction, an impeller carried by the rotor construction, an impeller chamber enclosing the impeller, said impeller being constructed and arranged to provide liquid under pressure which exceeds the pressure in said passage, and an orifice for supplying liquid from the impeller chamber to the passage, whereby said passage is maintained filled from the orifice and at a pressure determined by the escape means and excess liquid entering the passage from the orifice flowing through the escape means without affecting the pressure in the passage.
